[57] ABSTRACT

A switching device for driving of a tone band from an unwinding to a winding spool carrier, the end of said tone band being secured to said spool carrier of said unwinding tone band, which comprises drive means and a spool carrier. A drive shaft is provided for driving the spool carrier by the drive means. A disc fly-wheel mass is rotatably, but non-slidably mounted on the drive shaft. A coupling means is disposed between the drive shaft and the disc fly-wheel mass for joining rotation of the latter. A member is adjustable against elastic means and rotatably, but non-slidably mounted on said drive shaft. A shifting device for the member for shifting in dependency upon the transmission force of the coupling means against the force of the elastic means into an operative position, upon the transmission force being opposite as during an acceleration of the disc fly-wheel mass, and a switching device for stopping the drive, operable by the adjustable member, upon shifting the latter into its effective position.

SWITCHING DEVICE FOR A TONE BAND DRIVE

The present invention relates to a switching device for a tone band drive, in general, and to such tone band drive, which moves a tone band from an unwinding to a winding coil, and the end of which is anchored with the unwinding coil.

The switching device can be used for switching off the drive upon reaching the end of the band or also for reversing to the opposite driving direction. One of the previously known switching devices operates in such manner, that the tone band is guided about a pin, which is capable of swinging against the action of a spring, which pin performs a switching movement upon increase of the band's tension, due to reaching the band end. Such sensing elements which are in forced connection with the tone band, may disturb the uniformity of the band operation and are not useable everywhere, in consideration of the band operation, as for example, when the coils or spools are disposed in a box.

Another known switching device utilizes the increase in the band tension, for swinging the entire coil or spool in its plane, for the purpose of obtaining a switching movement. Aside from the fact, that this method requires a very massive construction, it is not suitable for transportable instruments, due to the danger of faulty switchings.

Another known switching-off device is based on the fact, that the speed of the coil is compared with the speed of a member driven by a motor, more slowly so that, upon stopping of the coil, a reversal of the relative speed occurs between the coil and the slower driven member, which is then also utilized in turn for a switching movement. Such device necessitates to overcome constantly a friction, which, in addition to the disadvantageous influence on the uniformity of the drive results in an undesired loss of energy for a fast re-coiling, and requires two switching-off devices for both directions of the band movements in instruments with play operations.

It is one object of the present invention, to provide a simple switching device, which is effective in normal play operation, as well as during fast re-coiling independently from the rotating direction of the coils, without a permanent additional loss in the driving power, due to friction, and which does not impair the movement uniformity of the tone band during the play operation.

It is another object of the present invention, to provide a switching device for a tone band drive, wherein a disc is coupled to one of both coil shafts by interpositioning a catch, whereby the catch shifts a switching member for the drive of the tone band, upon stressing in a direction opposite to the driving force of the swinging mass.

With these and other objects in view, which will become apparent in the following detailed description, the present invention, which is shown by example only, will be clearly understood in connection with the accompanying drawing, in which:

FIG. 1 is a schematic bottom plan view upon the bottom side of a tone driving device; and

FIG. 2 is a lateral sectional view along the lines 2-2, of FIG. 1.

Referring now to the drawing, the device, designed in accordance with the present invention, comprises a base-plate 1 on which are mounted two coil shafts 2 and 3, the upper ends 4 of which are adapted to engage the

coil bodies or spool carries 5 of a tone band 6, which is located in a cassette 7. The coil shaft 3 is driven by means of a pair of gears 8 and 9, an intermediate gear shaft 10, a friction coupling 11 with a belt pulley 12 and a belt 13, by means of a motor 14. The intermediate shaft 10 is mounted in a fork 15, which is capable of swinging about an axle 16. If the other coil shaft 2 is to be driven, the fork 15 is swung so far, until a gear 17, which meshes permanently with the gear 9, and is also mounted on the fork 15, comes into engagement with a gear 18 of the other coil shaft 2. This drive is used to wind the tone band in both directions for the normal recording-and reproduction-operation. In the coil drive a slip clutch 11 is required, in order to be able to wind the tone band 6 which is pulled with constant speed by a tone shaft 19 with a pressure roll 20, upon a coil, which rotates with a reducing number of revolutions due to the increasing winding diameter. In order to effect a fast recoiling of the tone band 6, the pressure roll 20 is lifted from the tone shaft 19, and a friction wheel (not shown) of larger diameter than the gear wheel 9 and seated on the intermediate gear shaft 10, is also selectively coupled with the coil shafts 2 and 3 (through axial shifting).

The intermediate gear shaft 10 has a square section 21, on which a sleeve 22 is axially slidable. A disc fly-wheel 24, freely rotatable relative to the intermediate gear shaft 10, without being axially shiftable, is disposed above the sleeve. The sleeve 22 has at the upper front side a saw-tooth shaped cam 29 and is pressed by a spring 23 against a complementary formed recess into a collar 26 of the disc fly-wheel 24, whereby the cam 29 presses against the face 28 of the disc fly-wheel 24, which face is strongly inclined toward the radial plane upon acceleration of the drive, the disc fly-wheel 24 is coupled with the coil shaft 3 in the direction of the driving movement.

When the tone band 6 has reached its end, the coil shaft 3, and thus also the sleeve 22, are suddenly brought to a stop, due to the rigid connection of the tone band end with the coil body 5.

Since the fly-wheel 24 does not find great resistance on the cam 29, it continues to rotate due to its mass inertia, whereby the cam 29 is axially shifted against the force of the spring 23 from the less inclined face 25 of the disc fly-wheel 24. This movement is used for switching the drive, whereby the sleeve 22 shifts a switching member 27 of the conventionally known switching means (not shown) for the tone band drive, the conventionally known switching means being not part of the present invention.

For a device for recording- and reproducing-operation, in such oppositely operation direction of the tone band, as disclosed by example, only one switching device is required, which is effective for fast recoiling as well as for normal operation. Whether the disc fly-wheel 24 is arranged on a shaft turning faster than the coil shaft, or on the coil shaft itself, depends upon the ratio of the lowest number of revolutions of the coil to the mass value of the disc fly-wheel 24. For portable machines, a small, fast-running disc fly-wheel is, in any case, more favorable. Simultaneously, the rotating disc has a stabilizing effect upon the uniformity of the band pull in the recording- and reproducing-operations.

While I have disclosed one embodiment of the present invention, it is to be understood, that this embodi-

ment is given by example only and not in a limiting sense.

I claim:

1. A switching device for driving of a tone band from an unwinding spool carrier to a winding spool carrier, the end of said tone band being secured to said unwinding spool carrier of the unwinding tone band, comprising

drive means,

coil shafts for driving said spool carriers, respectively, by means of said drive means, a freely rotatably mounted disc fly-wheel mass for stopping said drive means due to its mass inertia, a coupling means operatively disposed between said coil shafts and said disc fly-wheel mass for joining 15

rotation of the latter therewith, said coupling means including a drive force transmitting member, shiftable into a first position cooperating with said disc fly-wheel mass for said joining rotation therewith, and into a second position shift- 20

able out of joint rotation therewith, elastic means biasing said member into joint rotation with said disc fly-wheel mass,

said coupling means including said member being operatively connected to said coil shaft for joint rotation therewith and being rotated by said drive means with said coil shaft, and said coupling means including said member being non-rotatable when said coil shaft is stopped by means of the end of 30

said tone band stopping said winding spool carrier, said drive means being initially operative when said coil shaft is stopped via said end of said tone band, means cooperatively connected with said disc fly-wheel mass and said coupling means, for effecting, due to the mass inertia force of rotation of said 35

disc fly-wheel mass, a shifting of said member in dependency upon a transmission moment force of said coupling means relative said disc fly-wheel mass and against the force of said elastic means into said second position, upon said transmission 40

force being opposite as during an acceleration of said disc fly-wheel mass, and stopping of rotation of said member, and

switching means for stopping said drive means, and operable by said member, upon shifting of the latter into said second position.

2. The switching device, as set forth in claim 1, which includes

two of said coil shafts for driving said winding and unwinding spool carriers, respectively,

an intermediate shaft relatively coupled with one of said coil shafts, selectively, for transmission of the speed of said intermediate shaft to a lower speed of said one coil shaft,

said drive means for rotatably driving said intermediate shaft,

said disc fly-wheel mass is freely rotatably but axially immovably mounted on said intermediate shaft, and

said coupling means including said member is axially displaceably mounted on said intermediate shaft but mounted thereon for joint rotation therewith.

3. The switching device, as set forth in claim 2, wherein

said elastic means presses said member in axial direction towards said disc fly-wheel mass,

said member has a face engaging said disc fly-wheel mass and includes a cam extending in axial direction projecting beyond said face,

said disc fly-wheel mass has a recess complementary to said cam, and said cam and said recess constitute said shifting means,

an inclined face and a less inclined face on said cam, said inclined face constituting an abutment for said disc fly-wheel mass for joining the rotation of said coupling means and said intermediate shaft, and said less inclined face cooperating with said cam to effect an axial displacement of said member, upon a stopping of said one coil shaft, whereby said rotatably freely mounted disc fly-wheel mass axially displaces said member.

4. The switching device, as set forth in claim 2, further comprising

a friction slip clutch coupling between said drive means and said intermediate shaft.

5. The switching device, as set forth in claim 2, further comprising

means for selectively operatively driving either of said two coil shafts via said intermediate shaft.

6. The switching device, as set forth in claim 2, further comprising

first gear means secured to said intermediate shaft, second gear means secured to each of said two coil shafts, and

a pivotal fork, on which said first gear means is disposed, is pivotally mounted for selective engagement of said first gear means with said second gear means of either of said two coil shafts for driving engagement thereof.
